TEMPORARY LOAD SWITCH

David Charles Hubbard, Centralia, Mo., assignor
to A. B. Chance Company, Centralia, Mo., a
corporation of Missouri

Application July 7, 1951, Serial No. 235,640

4 Claims. (Cl. 200—146)

1

The present invention relates to temporary load switches, and is particularly concerned with the provision of an improved switching device for linemen, which will permit them to make either a connection or a disconnection to an energized circuit at a time when there is a possibility of current flow through the junction.

One of the objects of the invention is the provision of a switching device intended for temporary installation which can be used for interrupting the flow of current and for initiating the flow of current by connection to an already energized circuit.

According to the present practice, when it is necessary to make a connection to or disconnection from an energized line under conditions which may involve initiating the flow of current or disrupting the flow of current, operators have had a choice of three alternatives according to the prior art.

1. The operator may open switches or circuit breakers ahead of the connection point where the work is to be done and so stop the flow of current at that point. The objection to this procedure is that the switches or circuit breakers to be opened may be at a distance, and a loss of time is involved in the switching operation as well as a loss of revenue and of customer good will during the interruption of the circuit.

There is also a safety hazard involved, depending upon the proper coordination of all personnel and upon the proper choice of switches and choice of switching time.

2. The second alternative consists in breaking or disconnecting the connectors by hot line methods alone, involving the use of tools carried by long insulating poles. The objections to this method are that they may involve pitting and burning of the conductor and the connector, there is a possibility of establishing a long arc when effecting a disconnect and this arc, due to wind or other factors, may strike grounded equipment or carry over to another energized conductor, with resultant power failure and possible severe damage and injury to personnel.

3. The third alternative consists in the installation of disconnect switches at each point where equipment is installed and at each point where there are branch feeders. This is objectionable because of the increased cost of distribution construction and increased maintenance cost.

All of the foregoing objections may be eliminated by the use of the present temporary load switch, which may be installed temporarily at any point where it is desired to effect a connec-

2

tion or a disconnection to an energized line under possible current flow conditions without going to the expense of permanent disconnect switches, without danger of establishing long arcs, and without pitting or burning the conductors or connectors.

Another object of the invention is the provision of an improved load switch which may be used to break the circuit inside an insulated tube which confines the arc and gases to the inside of the tube, and to establish discharge ports that permit the exhaust of the gases in directions that are safe for the operator.

Another object of the invention is the provision of an improved temporary load switch which includes means for effecting a connection through a fuse whenever that is deemed advisable, so that if a fault still exists on the line the fuse will blow and protect the line and other equipment.

Another object of the invention is the provision of an improved temporary load switch construction which includes a minimum number of parts, which is simple in construction, sturdy, and capable of being used over and over again for interrupting or establishing heavy currents under conditions which involve maximum safety because of the operations all being performed at the same location.

Other objects and advantages of the invention will be apparent from the following description and the accompanying drawings, in which similar characters of reference indicate similar parts throughout the several views.

Referring to the drawings, of which there are three sheets, accompanying the specification,

Fig. 1 is a side elevational view partially broken away to reduce the length of the drawing, showing a temporary load switch embodying the invention;

Fig. 2 is a fragmentary sectional view taken on the plane of the line 2—2 of Fig. 1, looking in the direction of the arrows;

Fig. 3 is a fragmentary side elevational view of the lower ejector arm fixture in partial section with the switch blade omitted;

Fig. 4 is a top plan view of the cable ejector;

Fig. 5 is an enlarged fragmentary view similar to the lower end of Fig. 1, showing the details of attachment of the cable to the cable ejector lever;

Fig. 6 is a fragmentary side elevational view taken on the plane of the line 6—6 of Fig. 1, showing the construction of the upper cable supporting fixture which also carries a fixed blade contact;

Fig. 7 is a similar fragmentary sectional view taken on the plane of the line 7—7 through the same part of the mechanism as Fig. 6, showing the internal construction of the cable gripping lever;

Fig. 8 is a view in perspective of the blast deflector which is used in Figs. 6 and 7;

Fig. 9 is a view in perspective of the fixed contact for engaging the switch blade;

Fig. 10 is a fragmentary sectional view taken on the plane of the line 10—10 of Fig. 7, looking in the direction of the arrows;

Fig. 11 is a fragmentary sectional view similar to Fig. 5, showing an alternative mode of securement for the lower end of the cable;

Fig. 12 is a fragmentary sectional view taken on the plane of the line 12—12 of Fig. 1, looking in the direction of the arrows, showing the details of attachment of the upper fixture to a standard tap clamp at the connector aperture;

Fig. 13 is a fragmentary sectional view taken on the plane of the line 13—13 of Fig. 1, looking in the direction of the arrows;

Fig. 14 is a fragmentary sectional view taken on the plane of the line 14—14 of Fig. 3, showing an alternative assembly in which a connector bolt is employed;

Fig. 15 is a fragmentary sectional view taken on the plane of the line 15—15 of Fig. 1, looking in the direction of the arrows.

Referring to Fig. 1, the present temporary load switch is preferably provided with a tap clamp connector 28 for connection to the transmission line conductor. Such tap clamps are frequently used for temporary connections and various types of tap clamps may be employed.

For example, the tap clamp may have an upper fixed jaw member 21 and a lower movable jaw member 22. The upper fixed jaw member 21 may have a flat body flange 23 provided with a relatively large circular aperture 24 for receiving a clamp stick or the headed pin which is carried by the end of a disconnect stick.

The body flange 23 carries the laterally projecting flanges 25, 26, which form parts of a V-shaped groove for engagement above a line conductor 27, these flanges projecting from both sides of the flat body 23 to provide an elongated groove engaging the conductor.

The upper fixed jaw 21 customarily has a pointed beak 28, the lower guiding surface 29 of which guides the clamp over a conductor, and the body 23 supports a lower forwardly projecting arm 30, having a threaded bore 31 for receiving the threaded shank 32 of an eye bolt 33.

Eye bolt 33 has a ring or eye structure 34 at its lower end for engagement with a clamp stick, but in some embodiments of the invention the bolt 33 may be provided with a long insulated wooden handle permanently replacing the clamp stick.

The movable jaw 22 has a partially circular or V-groove 35 opposing the upper groove 36, and may be mounted for rotation upon the upper end 37 of the eye bolt 33, so that the eye bolt may rotate on the jaw 37.

The lower jaw 22 is guided in its sliding movement by guide flanges 38 engaging the opposite sides of a guide rib 39. I prefer to use a standard tap clamp, the body of which is provided with a circular through bore 40, surrounded by a conical depression 41, for receiving the usual apertured connector bolt.

In order that the eye bolt 33 or its wooden

handle may extend laterally in an accessible manner and so that the temporary load switch may extend downwardly to be actuated by means of a downward pull, the upper fixture 42 of the temporary load switch is preferably provided with a diagonally turned supporting lug 43 at its upper end. This supporting lug 43 may be generally hexagonal in cross section.

While lug 43 is generally hexagonal, it is so shaped on its under side that it has a V-shaped ridge fitting in the grooves of the tap clamp body. Lug 43 supports an integral lateral screw bolt extension 44 with a threaded end 45 for receiving a nut 46.

The integral screw bolt extension 44 replaces the usual apertured connector bolt in the aperture 40, and the hexagonal lug 43 rests against the groove 47 in the connector portion of the body 23, which grooves are usually employed for engaging the conductor.

The nut 46 engages the flat thrust surface 48 on the other side of the connector body and draws the lug 43 tightly against the body of the tap clamp. Thus the present temporary load switch is adapted to utilize any standard type tap clamp meeting these specifications because it can be attached to the tap clamp in place of the usual connector bolt.

The upper fixture 42 for the temporary load switch comprises a cast metal member having a cylindrical body portion 49, Fig. 10, at its left side, which portion is provided with a cylindrical bore 50 for receiving a reduced cylindrical portion 51 of the insulating fiber tube 52. The tube 52 is secured in this bore against the upper end 53 of the bore by one or more transverse metal pins 54 riveted in place and traversing the junction between the tube and the wall of the bore.

The cylindrical portion of the fixture 42 carries a pair of laterally projecting pivot flanges 55, 56, at the lower end of the tubular portion, these pivot flanges having through bores 57 serving as bearings for a screw bolt 58.

Screw bolt 58 is prevented from turning by a squared portion 59 on its shank and by the bore 57 being complementary in shape. The screw bolt 58 also carries a blast guard 60, shown in perspective in Fig. 8.

The blast guard is a substantially U-shaped sheet metal member formed with relatively square corners, and having a pair of attaching flanges 61, 62 provided with the squared aperture 63 in one and the round aperture 64 in the other. The squared aperture 63 fits the squared shank 59 on the bolt 58, aiding in holding the guard with its curved groove 65 tightly against the side of the tube 52, to which it is complementary.

The attaching flanges 61, 62 of the blast guard 60 are carried by the lower flat body 66, which covers the lower end of the fixture 42 between the pivot flanges 55 and 56, and prevents any downward blast of escaping gases resulting from the arc. Use of the guard also eliminates the necessity for trying to machine the parts about the flanges 55, 56 in such manner as to prevent escape of gases.

The bolt 58 also supports a fixed contact 67, forming part of a knife blade switch, the blade 70 of which is indicated at 68 in Fig. 1. This fixed contact comprises a strip of suitable resilient sheet metal of high conducting qualities, such as a copper alloy, which has a flat attaching portion 69 at its left end in Fig. 9, provided with a squared aperture 70 for the squared portion 59 of bolt 58.

The width of the fixed contact flange 69 is preferably such that its lower edge 71 strikes the inside of the bottom yoke 66 of the guard 60. Thus the squared aperture and engagement with the guard assure the fixed contact 67 being held against rotation.

Attaching flange 69 of fixed contact 67 is preferably curved outwardly at 72 and provided with a partially cylindrical portion 73, bringing its flat engaging portion 14 generally parallel to the side of the fixture body 42. The flat portion 14 is resiliently urged toward the fixture 42 by the curved part 73, and is initially spaced a distance less than the thickness of the blade 68, so that blade 68 will be tightly engaged between fixed contact 67 and the cylindrical part 49 of the fixture.

The fixed contact is also bent outwardly at 75, having a diverging blade guiding part 76 to insure the blade passing into the groove 77. Fixture 42 carries an integral blade stop 49a on its cylindrical portion 49, thus preventing the blade 68 from hammering against clip 67, which would gradually open and lose its gripping action. The fixture 42 is closed above the tube 52 by an upper wall 78, which forms part of a clamp lever housing 79.

The bolt 58 pivotally supports a spring pressed clamp lever 80. This clamp lever comprises a cast metal member having flat sides 81, 82, fitting between the flanges 55, 56, and provided with a circular bore 83, serving as a bearing on bolt 58.

The bolt 58 then passes through the following parts, beginning at the top of Fig. 10:

First the bolt passes through flange 62 of the guard, then through attaching flange 69 of the fixed contact, then through the pivot flange 55 of fixture 42, then through the clamp lever 80, then through pivot flange 56, and last through the guard flange 61, after which it is provided with a washer and a nut 84. The washer may be a spring lock washer.

Clamp lever 80 has a lower substantially cylindrical hub portion 85 about the bore 83, and has an upwardly extending arm 86 carrying a laterally extending arcuate clamping lug 87. The arcuate clamping lug 87 preferably has its forward end provided with a convex surface 88 terminating in a point 89, where the maximum clamping pressure is exerted.

Curved surface 88 and point 89 are adapted to engage a twisted multiple strand conductor cable 90, to press it against the inner plane surface 91, inside the housing 79, against which the cable 90 is clamped.

The pivot flanges 55 and 56 of the fixture 42 are extended upwardly to an arcuate top wall 92, which extends to the right in Fig. 7, and is also arcuate on the inside at 93 to permit movement of lever 80.

Arcuate top wall 92 has an abrupt shoulder 94, spaced from and behind the lever 80 at the right of Fig. 7, for limiting the movement of the lever in a clockwise direction. The top wall also includes a slightly lower portion 95, with a downwardly extending end wall 96, having a slanting surface 97 for retaining one end of a helical compression spring 98. The other end of this compression spring, which is loosely wound, is seated upon an integral lug 99, carried by the rear edge 100 of the clamp lever 80.

The clamp lever 80 also carries an outwardly extending actuating arm 101, Fig. 7, which extends out between the side walls 102 of the housing 79, and is formed with an upwardly turned end 103 to provide a hook recess 104 for

engagement with a clamp stick or disconnect stick.

The full line position of clamping lever 80, in Fig. 7, is that which it assumes when it is clamping a conductor cable 90, and the dotted line position is that to which it is moved by a clamp stick or disconnect stick by exerting a downward pull on the arm 101 to release the cable 90.

The insulating tube 52 has a cylindrical bore 105, and is made of the multiple layer insulating fiber of which fuse tubes are usually constructed. It is open at its lower end 106 for discharge of gases, and the clamp lever housing 79 also preferably has a lateral opening or window 107, Fig. 6, located to expose the clamped end of the cable 90 and the clamping end portion 88 of the clamp lever 80.

This window opening is bordered by outwardly beveled wall portions 108 and may be rectangular in shape, projecting laterally from the fixture 42 by means of a three-sided wall 109 to direct escaping gases laterally of the fixture and tube.

The window also permits the cable to be seen after it has been inserted into the clamping position so that the operator can see it as he clamps it to check its clamped condition.

The tube 52 carries a lower electrically conducting fixture 110, Fig. 1, preferably spaced slightly from the lower end 106, due to the depending arm 111 of the fixture 110.

Lower fixture 110 may comprise a cast metal member formed with a substantially cylindrical body 112, having a cylindrical bore 113, Fig. 2, of sufficient size to receive the insulating tube 52.

The fixture is secured on the insulating tube by a transverse riveted pin 114, so located at one side of the cylindrical portion 112 that the pin intersects the tube 52 as it passes through the fixture to prevent removal of the fixture from the tube or to prevent relative rotation.

Cylindrical body 112 preferably has a laterally projecting lug 115, the upper surface 116 of which serves as a stop for the switch blade 68 when it has been moved to the open-line position of Fig. 1.

Cylindrical body 112 also supports the laterally projecting connector portion 117, Fig. 2, which has a partially conical bore 118 and a pair of aligned V-grooves 119. The connector portion 117 has a flat surface 120, surrounding the circular bore 121, which ordinarily receives an apertured connector bolt 122.

Such a connector bolt 122 has a transverse aperture 123 at its upper end for receiving a conductor 124, which is clamped against the V-grooves 119 by pulling the shank 125 inward by means of a nut 126. The connector bolt is employed as shown in Fig. 14 when it is desired to attach a juncture wire to the connector 117.

Figs. 2 and 3 show an alternative assembly in which a special stud bolt 127 is employed. This bolt has a cylindrical body 128 and a narrow circular head 129 for receiving the tap clamp of a fused tapper. A fused tapper is used whenever it is desired to include a fuse in the circuit by means of the special stud bolt 127.

In some embodiments of the invention the special stud 127, including only a head 129, may be cast as an integral part of the fixture 110, eliminating the connector 117, and extending outward toward the right in Fig. 1 parallel to switch blade 68.

Stud bolt 127 also has a cylindrical shank 130 which passes through the connector portion 117, and it has a pair of laterally projecting integral lugs 131 which are clamped in the grooves 119

by nut 132. Thus the special stud bolt 127 may be fixedly clamped in the connector part of the lower fixture and used for attaching a fused tap-
per to interpose a fuse in the circuit.

The multiple strand, flexible cable 90, which is employed is usually preferably not provided with a fuse and it may be used over and over again except for such end portions as may become burned and may be cut off.

The lower conducting fixture 110 also has a laterally projecting arm 133, comprising a relatively flat web 134, bordered by laterally projecting upper and lower reinforcing flanges 135, 136. The arm 133 supports a substantially cylindrical hub 137, with a cylindrical bore 138 forming a bearing for a switch blade pintle 139, comprising a screw bolt.

The arm 133 preferably has an offset at 140, adjacent the hub 137, so that the thrust surface 141 of hub 137 may be located substantially in the plane of the same side of the upper fixture 42, so that the switch blade may best effect connection between the upper and lower fixtures.

Switch blade 68 may consist of an elongated rectangular section copper bar which is provided intermediate its ends, but closer to the lower end with a through bore 142 for receiving the screw bolt 139.

Screw bolt 139 passes through the hub 137 and blade 68, and is provided with a nut and with one or more spring clamp washers 143 on each side of the blade and fixture to establish a tight electrical connection between blade 68 and fixture 110 at all times, and to hold the blade frictionally in any position to which it may be moved.

The length of the blade 68 is sufficient so that it extends from the lower fixture 110 longitudinally of the tube 52 into engagement with and beyond the fixed contact 67. The blade 68 extends downwardly below the screw bolt 139 sufficiently to mount a cast metal ring fixture 144 and carries a similar ring fixture 145 adjacent its upper end but spaced from the fixed contact 67.

Each ring fixture 144, 145 is fixedly secured to blade 68 on the same side as the other in the same way except that the rings extend in opposite directions. Thus the ring 144 extends to the left to effect a closing of the switch blade 68 by a down pull, while ring 145 extends to the right to permit an opening pull to be exerted on the upper end of the blade.

Each ring fixture 144, 145 comprises an attaching body 146, formed with radiating reinforcing ribs 147 surrounding a tubular hub 148 for receiving a rivet 149, also passing through the blade. Rotation of the attaching flange 146 on the blade is prevented by engagement of blade 68 with a shoulder portion of the ring as shown in Fig. 15.

The switch blade 68 is now adapted to establish a connection from the upper conducting fixture 42 to the lower conducting fixture 110 which is in parallel with the braided cable 90. Thus the switch may be used to close the circuit when the temporary load switch is used with an empty tube, or it may be used preliminary to the opening of the circuit by means of the release of the braided cable 90.

The laterally projecting arm 133 of the lower fixture 110 has a diagonally and downwardly extending portion 150. This portion consists also of a pair of webs 151, 152, with reinforcing ribs 153, 154. The ribs 153, 154 merge into a thick end portion 155 of the arm 150, which is provided with a through bore 156 for receiving a screw bolt 157.

Screw bolt 157 has a cylindrical shank which slidably and rotatably engages a slot 158 in an ejector arm 159. The screw bolt 157 has a reduced threaded portion which is threaded into the bore 156, leaving the enlarged portion which fits the slot 158 of predetermined length, fitting the width of the ejector lever 159.

A washer 160 on the screw bolt 157 aids in guiding the ejector arm 159, which must slide freely and also pivot freely. The lower end of the thickened portion 155 may be formed with serrations, such as a ridge 161, at the juncture of two diagonal surfaces 162, 163. These surfaces are for clamping the braided cable 90.

The ejector lever may comprise an elongated metal member having an upwardly extending flat web 164, containing the slot 158. Web 164 also has an aperture 165 in which one end of the tension spring 166 is hooked. The other end of helical spring 166 is hooked in an aperture 167 in a special rib 168, extending downwardly on web 152 from hub 141.

The spring is initially tensioned so that it draws the ejector lever 159 up against the end of the tube 52, and also tends to pivot the ejector lever in a clockwise direction when the bolt 157 is in the lower end of slot 158.

Ejector lever 159 has a tail 169 at its left end, Figs. 3, 4 and 5, for engagement with the thumb or fingers while installing the cable 90. Ejector lever 159 also has the laterally extending clamping portion 170, formed with a pair of ridges 171, 172, separated by a V-shaped groove complementary to the ridge 161.

Ejector lever 159 also has a laterally extending finger 173 at its right end, with an upwardly convex portion 174 for receiving the stranded cable 90 as it is bent backward and upward upon emerging from the tube 52.

The mode of installation of the stranded cable 90 is as follows:

One end of the cable is inserted in the bottom 106 of tube 52, and the cable has sufficient stiffness to be pushed into the tube until it appears at the window 107. The clamping lever 80 is retracted from the adjacent inner surface of the fixture by pushing down on the actuating end 101 so that the cable may be pushed up under the end of lever 80.

The lever is permitted to be forced against the cable, as shown in Fig. 7, by means of its spring. The upper end of cable 90 is thus secured in the upper conducting fixture 42 and the cable is then passed under the curved portion 174 of the ejector lever 159 and pulled taut until the end of the ejector lever strikes the end of the tube.

The cable is then passed upward over the top of the clamping ridges 171, 172 of the ejector lever, behind the web 164 and under the ridge 161. At this time these clamping surfaces may be separated by pushing down on the tail 169 and upon releasing the tail 169 with the cable held taut, the cable is clamped with the ejector lever 159, so tensioned that it tends to draw the cable out of the tube.

The circuit may be broken at any time by pulling down on the actuating arm 101 of the clamping lever 80, releasing the upper end of the cable, whereupon the cable is pulled out of the tube to break the circuit in the tube.

The resulting arc and gases are discharged out of the bottom of the tube and laterally of the window 107, extinguishing the arc without danger to the operator, who is preferably located at some distance and who manipulates this device with a clamp stick.

In another modified form of the invention, shown in Fig. 11, the ejector lever is of the simple pivoted type without the slot or clamping surfaces, but having a thumb screw connector on the end of the bolt 157, under which the cable is clamped.

The cable being clamped at the center of rotation of the ejector lever, there is practically no sliding movement of the cable on the end portion 174 of the lever, and a minimum amount of friction so that the ejector lever may pull out the cable as quickly as possible.

The specific mode of releasing the cable and breaking a circuit has been previously described, and the following is a description of the mode of manipulation of the temporary load switch for safely breaking circuits under load or for connecting circuits under load.

Whenever a circuit is to be disconnected under load, the following steps should be taken:

1. A flexible, braided conductor should be installed in the tube and clamped above and below under tension as described.

2. The switch blade 68 should be closed into engagement with the clip or fixed contact 67.

3. A temporary jumper conductor should be connected to the terminal connector 43.

4. The permanent connection from line to equipment which is to be broken and removed, is now by-passed by connecting the tap clamp 20 to one side of this connection and connecting the temporary jumper to the other side of this permanent connection, using hot line tools.

5. The by-passed permanent connection is now disconnected with hot line tools, but the load is temporarily carried through this temporary load switch.

6. A disconnect pole is inserted in the ring 45 and the blade 68 is opened by means of a downward pull until it engages stop 116. The entire load now passes through the braided cable conductor 90.

7. Using the same disconnect stick, the stick is applied to the actuating arm 101 of the clamping lever 90, and a light downward pull releases the upper end of the cable 90. This breaks the circuit safely within the tube 52.

8. The temporary load switch is now removed by removing the tap clamp 20 and by disconnecting the by-passing jumper.

In brief, the permanent connection has been disconnected without hazard by by-passing it with this temporary load switch, then disconnecting it while the load is carried by the switch, then opening the blade of the switch and breaking the circuit at the cable inside the tube.

When an energized circuit is to be connected to another line or equipment under conditions which may involve the flow of current, the temporary load switch may also be employed. This may occur whenever it is necessary to make a connection directly to a transformer or to a bank of transformers to which a load was previously attached; or a feeder may similarly be reconnected through this switch after storm damage or whenever an unknown consumer load is still present on the circuit.

Such a load makes it hazardous to connect a feeder directly to an energized line by means of clamps because the application of a clamp to the line may not be accomplished without some rattling about of the clamp on the line, which results in arcing, burning and pitting of the clamp and the conductor.

The mode of manipulation of the tool to con-

nect to an energized line under load is as follows:

1. The switch blade 68 is moved to the open position against the stop 116. The flexible braided cable 90 is omitted and the tube is empty.

2. A temporary jumper is attached to the lower fixture 110 at its connector.

3. The temporary jumper is connected to the feeder transformer or other equipment.

4. Using a conventional hot line tool the tap clamp 20 is then attached to the energized circuit.

5. The blade 68 is closed by means of a disconnect stick, pulling down on the ring 144. The short lever arm of the ring 144 and the resisting friction of the blade give the blade a snap action in closing. The new circuit has now been energized under load.

6. A permanent connection for the new circuit or equipment is now installed with hot line tools, by-passing the temporary load switch.

7. The temporary switch and temporary jumper are now removed.

Wherever there may be a fault still existing on the line, it may be desirable to provide fuse protection in series with the temporary switch. This can be done by using the special stud 127 in the lower connector 117, and by hanging a fused tapper on this stud so that the temporary jumper can be attached to the lower end of the fused tapper.

The circuit, when closed by the blade 68, now passes through a fused tapper as well as the temporary load switch. If a fault still exists on the line the fused tapper will blow, cutting out the circuit and preventing damage to the other equipment.

It will thus be observed that I have invented an improved temporary load switch which permits the disconnection of high voltage circuits under load under safe conditions at any point where it is desirable to effect a disconnection.

It is also capable of being used in connecting circuits where there may be a possible load, without hazard, and it may also be used to connect circuits where a fault still exists by including a fused tapper in the circuit.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. A temporary load break switch comprising an insulating tube provided at its lower end with a metal fixture fixedly secured on said tube at a point spaced from its end, said fixture being provided on one side with a connector for attachment to a conductor and extending in the opposite direction and downwardly toward the end of the tube, a pivot pin carried by the downward end of said fixture, and said fixture presenting a downwardly ridged surface, and an ejector lever provided with a slot for pivotal and sliding movement on said pivot pin, said ejector lever presenting an upwardly grooved surface opposite said ridged surface for clamping the end of a cable, and said ejector lever extending to a point adjacent the open lower end of said tube and having a lat-

erally projecting arm engaging above said cable, spring means engaging said ejector lever on its side opposite to the tube and tensioning said ejector lever so that its end adjacent said tube tends to pull the cable out of said tube, and said spring also urging said ejector lever to clamp the end of said cable, a second fixture carried by the upper end of said tube, said second fixture comprising a tubular metal member secured to said tube, and having a flat arcuate extension projecting laterally, said arcuate extension having a pair of parallel walls supporting a pintle member at the center of its arc, and said pintle pivotally supporting a radially extending lever having an arcuate clamping extension projecting above the end of said tube, and having an outwardly projecting actuating end curving upwardly, a compression spring in said arcuate extension urging said lever into clamping engagement with the side wall of said upper fixture, and a cable in said tube, having its upper end clamped against said side wall by said lever and its lower end subjected to tension by said ejector lever.

2. A temporary load break switch comprising an insulating tube provided at its lower end with a metal fixture fixedly secured on said tube at a point spaced from its end, said fixture being provided on one side with a connector for attachment to a conductor and extending in the opposite direction and downwardly toward the end of the tube, a pivot pin carried by the downward end of said fixture, and said fixture presenting a downwardly ridged surface, and an ejector lever provided with a slot for pivotal and sliding movement on said pivot pin, said ejector lever presenting an upwardly grooved surface opposite said ridged surface for clamping the end of a cable, and said ejector lever extending to a point adjacent the open lower end of said tube and having a laterally projecting arm engaging above said cable, spring means engaging said ejector lever on its side opposite to the tube and tensioning said ejector lever so that its end adjacent said tube tends to pull the cable out of said tube, and said spring also urging said ejector lever to clamp the end of said cable, a second fixture carried by the upper end of said tube, said second fixture comprising a tubular metal member secured to said tube, and having a flat arcuate extension projecting laterally, said arcuate extension having a pair of parallel walls supporting a pintle member at the center of its arc, and said pintle pivotally supporting a radially extending lever having an arcuate clamping extension projecting above the end of said tube, and having an outwardly projecting actuating end curving upwardly, a compression spring in said arcuate extension urging said lever into clamping engagement with the side wall of said upper fixture, and a cable in said tube, having its upper end clamped against said side wall by said lever and its lower end subjected to tension by said ejector lever, the said latter pintle also supporting a substantially U shaped blast guard, the yoke of which extends below said pintle and below said lever to prevent the downward blast of gases past said lever, the said pintle comprising a screw bolt and nut, and said screw bolt also clamping the attaching end of a resilient spring and contact which extends about said fixture close to the side thereof and is provided with an outwardly flaring end for guiding a switch blade, and a switch blade pivoted on said lower fixture and frictionally held against rotation by a clamping bolt, the said switch blade engaging said upper contact and swinging downwardly for disengagement.

3. A temporary load break switch comprising an insulating tube provided at its lower end with a metal fixture fixedly secured on said tube at a point spaced from its end, said fixture being provided on one side with a connector for attachment to a conductor and extending in the opposite direction and downwardly toward the end of the tube, a pivot pin carried by the

downward end of said fixture, and said fixture presenting a downwardly ridged surface, and an ejector lever provided with a slot for pivotal and sliding movement on said pivot pin, said ejector lever presenting an upwardly grooved surface opposite said ridged surface for clamping the end of a cable, and said ejector lever extending to a point adjacent the open lower end of said tube and having a laterally projecting arm engaging above said cable, spring means engaging said ejector lever on its side opposite to the tube and tensioning said ejector lever so that its end adjacent said tube tends to pull the cable out of said tube, and said spring also urging said ejector lever to clamp the end of said cable, a second fixture carried by the upper end of said tube, said second fixture comprising a tubular metal member secured to said tube, and having a flat arcuate extension projecting laterally, said arcuate extension having a pair of parallel walls supporting a pintle member at the center of its arc, and said pintle pivotally supporting a radially extending lever having an arcuate clamping extension projecting above the end of said tube, and having an outwardly projecting actuating end curving upwardly, a compression spring in said arcuate extension urging said lever into clamping engagement with the side wall of said upper fixture, and a cable in said tube, having its upper end clamped against said side wall by said lever and its lower end subjected to tension by said ejector lever, the said latter pintle also supporting a substantially U shaped blast guard, the yoke of which extends below said pintle and below said lever to prevent the downward blast of gases past said lever, the said pintle comprising a screw bolt and nut, and said screw bolt also clamping the attaching end of a resilient spring and contact which extends about said fixture close to the side thereof and is provided with an outwardly flaring end for guiding a switch blade, and a switch blade pivoted on said lower fixture and frictionally held against rotation by a clamping bolt, the said switch blade engaging said upper contact and swinging downwardly for disengagement.

4. A temporary load break switch comprising an insulating tube provided at its lower end with a metal fixture fixedly secured on said tube at a point spaced from its end, said fixture being provided on one side with a connector for attachment to a conductor and extending in the opposite direction and downwardly toward the end of the tube, a pivot pin carried by the downward end of said fixture, and said fixture presenting a downwardly ridged surface, and an ejector lever provided with a slot for pivotal and sliding movement on said pivot pin, said ejector lever presenting an upwardly grooved surface opposite said ridged surface for clamping the end of a cable, and said ejector lever extending to a point adjacent the open lower end of said tube and having a laterally projecting arm engaging above said cable, spring means engaging said ejector lever on its side opposite to the tube and tensioning said ejector lever so that its end adjacent said tube tends to pull the cable out of said tube, and said spring also urging said ejector lever to clamp the end of said cable, a second fixture carried by the upper end of said tube, said second fixture comprising a tubular metal member secured to said tube, and having a flat arcuate extension projecting laterally, said arcuate extension having a pair of parallel walls supporting a pintle member at the center of its arc, and said pintle pivotally

supporting a radially extending lever having an arcuate clamping extension projecting above the end of said tube, and having an outwardly projecting actuating end curving upwardly, a compression spring in said arcuate extension urging said lever into clamping engagement with the side wall of said upper fixture, and a cable in said tube, having its upper end clamped against said side wall by said lever and its lower end subjected to tension by said ejector lever, the 10 said latter pintle also supporting a substantially U shaped blast guard, the yoke of which extends below said pintle and below said lever to prevent the downward blast of gases past said lever, the said pintle comprising a screw bolt and nut, and said screw bolt also clamping the attaching end of a resilient spring and contact which extends about said fixture close to the side thereof and is provided with an outwardly flaring end for guiding a switch blade, and a switch blade pivoted on said lower fixture and frictionally held against rotation by a clamping bolt, the said switch blade engaging said upper contact and swinging downwardly for disengagement, said

switch blade extending downwardly past its pivot and being provided with a ring fixedly secured thereto, and projecting backwardly from said tube and lower fixture for actuating said blade 5 with a snap action.

DAVID CHARLES HUBBARD.
